UNITED STATES PATENT OFFICE.

JOSEPH DE ROSE, OF PATERSON, NEW JERSEY.

NON-REFILLABLE BOTTLE.

1,005,106.

Specification of Letters Patent.

Patented Oct. 3, 1911.

Application filed June 12, 1911. Serial No. 632,798.

To all whom it may concern:

Be it known that I, JOSEPH DE ROSE, a citizen of the United States, residing at Paterson, in the county of Passaic and State 5 of New Jersey, have invented certain new and useful Improvements in Non-Refillable Bottles, of which the following is a specification.

This invention relates to non-refillable 10 bottles and more particularly to that class of bottle valves which are spring actuated.

An object of the present invention is to provide a bottle valve which, when inserted in the neck of the bottle can only be opened 15 by the pressure of liquid thereupon and therefore cannot be refilled by shaking or jarring the bottle.

Another object of the invention is to construct a non-refillable bottle with a few 20 parts and yet accomplish in an efficient manner the same results as derived from the use of more complicated structures.

By constructing a valve in accordance with the present invention, the several parts 25 will be easily and quickly assembled without the use of tools and thereby rendered very desirable.

For a full understanding of the present invention, reference is to be had to the following description and to the accompanying drawings, in which—

Figure 1 is a vertical sectional view of the present invention applied to the neck of a bottle; Fig. 2 is a similar view disclosing 35 the valve as it appears when liquid is being poured from the bottle; Fig. 3 is a front elevation of the plug or bottle valve; Fig. 4 is a side elevation thereof; Fig. 5 is a transverse sectional view taken on the line 5—5 40 of Fig. 1; and Fig. 6 is a vertical sectional view taken on line 6—6 of Fig. 4.

Throughout the following detail description and on the several figures of the drawings, similar parts will be referred to by like 45 reference characters.

In carrying out the present invention, the bottle 1 is provided with an abutment or shoulder 2 which is formed at the base of the neck, although the exact location may 50 be varied if desired. The shoulder 2 is provided with a tapering opening which is adapted to receive the tapering terminal 3 of the plug 4. This tapering portion 3 may be ground to form a water-tight joint with 55 the shoulder 2.

The plug or body 4 comprises upper and

lower portions 5 and 6 respectively, said upper portion 5 being provided on its peripheral edge with semi-circular grooves 7 which are adapted to coincide with similarly 60 formed grooves 7' in the neck of the bottle when the body is in position. Between the terminals of the semi-circular grooves 7 is a longitudinal groove 8 which is prevented from having communication with the 65 grooves 7 by the walls 9. The under surface of the cap or upper portion 5 is provided with a semi-circular groove which is adapted to coincide with a similarly formed groove on the upper face of the lower portion 6, and into this groove is inserted any 70 desirable cementing composition for sealing the two sections together.

The lower portion 6 is cylindrical in shape and has a central reduced portion 10 forming 75 an annular channel for the passage of the liquid thereabout. The grooves 8 which are formed in the upper section 5 are extended to this annular channel 10, whereby communication is obtained between the latter 80 and the mouth of the bottle. On the lower edge of the annular passage 10 and in alignment with the groove 8 is a groove 8' which extends partially the length of the portion intermediate said groove 10 and the lower 85 edge of the section 6. To obtain communication between the passage 10 and the interior of the bottle, a pair of grooves or passage-ways 11 are provided on the opposite sides of the section 6 and approximately 90 mid-way between the grooves 8 which are formed on the upper portion of the section 6.

On the under surface of the section 6 is a depending tubular section or spout 12 which has its lower terminal tapered as at 3 95 for the purpose hereinbefore specified. This tubular member 12 is provided with a passage-way 13 which opens communication between the interior of the bottle and the portion 14 intermediate the shoulder 2 and the section 6. After the liquid has passed through the passage 13 into the compartment 14, the path of the fluid is then through the grooves 11, about the annular passage 10 and out the grooves 8. 100

A spring actuated valve is provided for closing the passage 13, the former comprising 110 a journal 15 seated in the grooves or circularly shaped seat 16 formed at the base of the section 6. This journal 15 is provided with an arm 17 extending into the compartment 14 and is provided at its lower terminal

with an opening or aperture 18 adapted to loosely receive a stem 19 of a valve 20, said valve 20 being of any desirable material and adapted to close the mouth of the passage 5 13. The interior of the section 6 is hollow, as at 21 and into which projects an arm 22 detachably or otherwise mounted in a groove 23 formed in the journal 15. This arm 22 has secured thereto a spring 24, the free terminal of which is adapted to bear on the inclined face of the recess 25 formed in the under surface of the cap section 5.

From the foregoing and by reference to the drawings it will be noted that the pressure of the liquid will overcome the resistance of the spring 24 and cause the valve to open whereby the liquid may be easily poured from the bottle. As soon as all of the liquid has escaped, the spring 24 will cause the valve to close and prevent the insertion of fluid into the bottle. It will further be observed that the valve can not be opened by shaking the bottle up and down nor under normal conditions will said valve be opened by any other sort of jarring.

The journal 15 is insertible through the transverse circular opening 16 and is retained in an operative position on the seat 16 by the stem or arm 22 being inserted in the slot or opening 23 whereby any lateral movement of said journal member is eliminated.

Should any attempt be made to insert a wire or other instrument through the passageway 8, the former will be prevented from coiling or turning around the annular passageway 10 by the terminal of said wire entering the extension 8' and catching therein or otherwise distorting the instrument 40 and making it difficult to force the latter about said annular passageway.

Having thus described my invention, what is claimed as new is:

1. In combination, a bottle having a neck 45 provided with a shoulder therein, said shoulder having an opening therethrough, a hollow body mounted within the neck comprising upper and lower sections secured together, the lower section thereof having an annular 50 passage, passage-ways extending upwardly therefrom and in alinement with similarly shaped passage-ways provided in the upper section, and downwardly extending passage-ways from said annular passage to the interior of the bottle, a depending tubular section carried by said lower section and fitting snugly in the opening in said shoulder, said tubular section being provided with a passage therein, a journal mounted in said body 55 and closing communication between the interior of said body and that of the bottle, an arm formed on said journal, a valve carried by said arm and adapted to close said last named passage, and spring means with- 60 65 in said body and secured to said journal for

operating the latter, the under surface of said upper section being recessed to receive said spring means.

2. In combination, a vessel having an outlet, a body insertible into said outlet comprising an upper cap section, a lower section provided with a passage way therein leading from the interior of the vessel, a journal mounted on said lower section, an arm carried by the journal, a valve carried by said arm and adapted to close said passage-way, and a leaf spring carried by said journal, said cap section being recessed to receive said spring to create a tension.

3. In combination, a vessel having an outlet, a body insertible into said outlet and comprising a cap section, a hollow section provided with a passage way therein leading from the interior of the vessel, a journal mounted on said lower section, an arm carried by the journal, a valve carried by said arm and adapted to close said passage way, and spring means within the hollow portion of said hollow section and secured to said journal, said cap section being recessed to receive said spring means.

4. In combination, a vessel having an outlet, a body insertible into said outlet and comprising a cap section, a hollow section provided with a passage way therein leading from the interior of the vessel, a journal mounted on said lower section, an arm carried by the journal, a valve carried by said arm and adapted to close said passage way, a second arm mounted on the journal and adapted to prevent dislodgment of the latter, and spring means carried by said second arm and adapted to be put under tension by said cap section.

5. A bottle valve comprising a hollow body having a passage way therein and also a transverse opening, a journal mounted in said transverse opening and provided with a groove therein, an arm insertible through said hollow body and into said groove to prevent the dislodgment of the journal, and means carried by said journal for closing said passage way.

6. A bottle valve comprising upper and lower sections, said upper section having a recess formed therein and said lower section being hollow and provided with a transverse opening therein, a journal mounted in said transverse opening and closing communication between the hollow portion of the body and the exterior atmosphere, an arm carried by the journal and projecting into said hollow portion, spring means secured to said arm and bearing in said recess, the aforesaid sections having liquid conducting passage-ways therein, and means carried by said journal for closing the passageways.

7. In combination, a vessel provided with an outlet, a hollow body secured in said outlet and having a transverse opening

therein, a depending section formed in said body having a passageway therein through which the contents of the vessel may pass, a journal mounted in said transverse opening, a valve carried by said journal and adapted to open and close said passageway, and means carried by said journal and projecting into the hollow portion of the body, said means being limited in its movement by

the inner walls of the body and thereby preventing the dislodgment of said journal.

In testimony whereof I affix my signature in presence of two witnesses.

JOSEPH DE ROSE.
